UNITED STATES PATENT OFFICE.

MARY C. COLLIER, OF WASHINGTON, DISTRICT OF COLUMBIA.

FOLDING CRIB.

SPECIFICATION forming part of Letters Patent No. 732,618, dated June 30, 1903.

Application filed February 21, 1903. Serial No. 144,359. (No model.)

To all whom it may concern:

Be it known that I, MARY C. COLLIER, a citizen of the United States, residing at Washington, in the District of Columbia, have 5 invented new and useful Improvements in Folding Cribs, of which the following is a specification.

This invention relates to a folding crib for attachment to the side rail of a bed and embodying structural features whereby it may be reduced to compact form when not in use.

The object of the invention is to provide a strong and durable crib having folding extensible parts which can be readily disposed and 15 adjusted to adapt the crib for use or quickly folded and retracted to reduce the crib to compact form for storage or transportation.

The invention consists in the construction and arrangement of the several parts, which 20 will be more fully hereinafter described and claimed.

In the drawings, Figure 1 is a perspective view of a portion of a bedstead, showing the improved crib applied thereto in operative 25 position. Fig. 2 is a top plan view of the crib with the mattress removed. Fig. 3 is a transverse vertical section on the line 3 3, Fig. 2. Fig. 4 is a top plan view of the crib shown folded. Fig. 5 is a horizontal section through 30 a portion of one of the legs and the guiding means therefor.

Similar numerals of reference are employed to indicate corresponding parts in the several views.

35 The numeral 1 designates the bottom of the crib, which is composed of a plurality of longitudinally-arranged slats 2, riveted or otherwise secured to end bars 3, having their inner ends extended to form hooks 4 to fit over 40 the upper edge of the side rail of a bed, as shown by Fig. 1. The opposite extremities of the slats 2 are exposed on the upper surface of the end bars 3 and have their terminals 5 upturned at right angles and secured 45 against the outer surfaces of lower end slats 6, which serve as supports and attaching means for the end members of the crib, as will be more fully hereinafter set forth. The outer extremities 7 of the end bars 3 are turned 50 upwardly at right angles and formed with terminal knuckles 8.

The inner portion of the crib is fully open,

and to the slats 6 end members 9 are hinged and constructed in the form of slatted frames having the lower slats thereof connected to the 55 slats 6 by hinges 10. An outer side frame 11 is hinged to the knuckles 8 of the outer angular extremities of the end bars 3, the said frame 10 being composed of longitudinal slats 12, connected by vertical end bars 13. The 60 end bars 13 have the opposite side edge portions thereof inwardly bent to provide guides 14, the lower terminals of the bars 13 being extended below the guide portions thereof and connected to the knuckles 8 by suitable 65 pintles. Within the guides 14 legs 15 are adjustably mounted and have their lower ends bent inwardly to form feet 16, which are adapted to rest on the floor or other support on which the bed to which the crib is attached 70 is disposed. The upper terminals of the legs 15 are enlarged to form heads 17, which project outwardly from the guides 14 and have screw-threaded apertures therein to receive clamping-screws 18, which run completely 75 through the said heads to impinge against the outer vertical walls of the guides to thereby hold the legs immovable after a proper adjustment has been made.

The end frames have their lower edges held 80 at such distance above the bottom of the crib as to practically fold over and rest on the upper surface of a mattress 19, and the lower edge of the outer side frame 12 is held high enough above the mattress and the upper 85 edges of the slats 6 to compensate for the thickness of the mattress and the end frames when all the parts are folded inwardly in horizontal planes. By this means the mattress 19 will be held firmly in the crib when the parts 90 are folded ready for instant use, when the several frames are turned outwardly in erect position, as shown by Fig. 1. When the outer side frame 12 is folded inwardly, the legs 15 are released and also pushed inwardly to reduce the projection thereof and render the entire crib compact for storage or transportation, and by bending the ends of the legs to form the feet 16 another advantage is gained by having the said bent leg-terminals 95 inwardly directed close to the adjacent portions of the crib, thereby preventing them catching on adjacent objects or forming injurious projecting ends.

When the outer side and end frames are open, it is obvious that some positively-operating means must be provided for securing said frames in immovable relation, and for this purpose a hasp-bar 20 is pivoted at its one end to the outer edge of each guide, an opening or slot 21 being formed in the free end of said hasp-bar, and movable across said slot is a hook 22, pivoted to the outer side of the bar. The free end of the hasp-bar is adapted to fit over a staple 23, secured to the outer slat of each end frame, and when the staple is projected through the slot 21 the hook 22 is thrown down in engagement with said staple to thereby firmly lock the outer side and end frames in immovable erect position. It will be seen that the hasp-bars 20 serve as bracing means at the points where they engage the end frames and being located on the outside are less apt to be released by the child within the crib.

By having the legs 15 adjustable different heights of bed-rails can be readily accommodated, and to render the attachment of the legs to the guides more reliable the inner opposing surfaces of the side edges of said guides are inclined inwardly, and the heads 17 at their inner portions are formed with outwardly-inclined flanges 24, as clearly shown by Fig. 5. It will be seen that from the construction just explained the legs will be prevented from springing outwardly through the openings of the guides, and when the clamping-screws 18 are turned to bind the legs in fixed adjusted positions the resistance to accidental slipping movement of the legs will be materially increased.

To render the crib more durable, it is preferred that all the parts thereof be constructed of metal, and by utilizing strap-iron for this purpose the cost of manufacture will be reduced to a minimum. It is also proposed to ornament the several parts by plating, painting, or enameling the same and also to vary the proportions and dimensions, as well as the minor details of construction, without departing from the spirit of the invention. For conveniently carrying the crib in its folded condition a grip loop or ring 25 is secured to the center of the outer portion of the bottom thereof, and as all the parts of the crib

when folded are well balanced this grip loop or ring will efficiently serve its intended use.

Having thus fully described the invention, what is claimed as new is—

1. A crib, comprising a bottom having end bars with hooks at their inner terminals and outer upwardly-bent extremities, end frames hinged to the bottom and foldable inwardly over the latter, an outer side frame hinged to the upwardly-bent outer extremities of the end bars, legs adjustably held at the opposite ends of the outer side frames, the bottom end frames and outer side frames having rigid slats extending longitudinally thereof, and means for holding the frames in immovable erect position. 55

2. A crib, comprising a bottom having a series of longitudinal rigid slats with upturned angular ends, end bars to which the opposite extremities of the said slats are secured, said end bars having inner hooks and outer upturned ends, rigid end slats secured to the upturned angular ends of the bottom slats, end frames hinged to the said end slats and also having rigid slats, an outer side frame hinged to the outer upturned ends of the end bars and having rigid slats, legs adjustably held at the opposite ends of the outer side frame, and means for securing the frames in erect position. 70

3. A crib, comprising a bottom with inner attaching-hooks, end frames having their lower portions movably attached at an elevation above the bottom to compensate for the thickness of a mattress when infolded, an outer side frame having its lower portion hinged at an elevation above the plane of hinged attachment of the end frames to compensate for the thickness of a mattress and the infolded end frames, the bottom end frames and outer side frame having rigid slats, legs adjustably held at opposite ends on the outer side frame, and means for locking the frames in immovable erect position. 90

In testimony whereof I affix my signature in presence of two witnesses.

MARY C. COLLIER.
